MICROTOME

Edward Bausch, Rochester, and Gustave Fassin,
Irondequoit, N. Y., assignors to Bausch & Lomb
Optical Company, Rochester, N. Y., a corpora-
tion of New York

Application April 26, 1935, Serial No. 18,484

12 Claims. (Cl. 88—40)

The present invention relates to microtomes for cutting sections of materials for microscopic examination.

One of the objects of the present invention is to provide a variable feed microtome which is durable and rugged in construction yet efficient and accurate in operation. Another object is to provide a compact microtome having a built-in power drive. A further object is to provide a microtome having a reciprocating carriage and having a linear feed mechanism which does not apply torque to the carriage. Still another object is to provide a new and improved pawl and ratchet feed mechanism for a microtome in which mechanism the pawl is withdrawn from the ratchet during its non-feeding stroke. A further object is to provide a new and improved limiting means for the feed mechanism of a microtome. A further object is to provide a new and improved object holder for a microtome. A still further object is to provide a new and improved knife supporting clamp for a microtome. These and other objects and advantages reside in certain novel features of construction, arrangement and combination of parts as will hereinafter be more fully set forth and pointed out in the appended claims.

In the drawings:

Fig. 1 is a perspective view showing one side of a microtome made in accordance with this invention.

Fig. 2 is a perspective view showing the other side thereof.

Fig. 3 is a top plan view of the interior mechanism with parts in section.

Fig. 4 is a rear view of the interior mechanism.

Fig. 5 is a side elevation of the interior mechanism with parts in section.

Fig. 6 is a detail view of the pawl and ratchet mechanism in side elevation.

Fig. 7 is a fragmentary view of same in front elevation.

Fig. 8 is a detail view showing the object holder and clamp in vertical section.

A preferred embodiment of this invention is illustrated in the drawings wherein 10 indicates the base of a microtome having a feed mechanism housing indicated generally at 11 and a knife holder indicated generally at 12. The feed mechanism housing 11 has a front wall 13, two side walls 14 and 15 and a cover 16 hinged near the base 10 for closing the top and rear.

A shaft 17 mounted in bearings 18 and 19 extends through the side wall 14 and has a fly wheel 20 and an operating handle 21 secured thereto outside of the housing 11. Within the housing,

the shaft 17 is connected by suitable gears 22 and 23 to a shaft 24 which is in turn connected to the motor 25 through a suitable one-way drive indicated generally at 26. An eccentric 27 is secured to the inner end of the shaft 17 for a purpose to be described later.

The front wall 13 is formed with a vertical slot 28 and a plate 29 is mounted in bearings on each side of the slot 28 for vertical reciprocatory motion. A carriage 30 is secured to the plate 29 extending rearwardly therefrom in a horizontal direction and has on one side a horizontal recess 31 in which a block 32 is slidable. This block is pivotally connected to the eccentric 27 so that rotation of the shaft 17 will reciprocate the carriage 30 and the plate 29. Two members 33 and 34 are secured to the top of the carriage 30 to form a second horizontal guideway 35. An object holder 36 is slidably mounted in the guideway 35 with its axial center passing through the center of the plate 29.

A screw 37 is journalled in bearings 38 and 39 within the carriage 30 with its axis parallel to the axis of the object holder 36. The object holder 36 is provided with an aperture 40 through which the nut 41 extends to engage the screw 37. The top portion 42 of the nut 41 extends beyond the aperture 40 and is securely fastened to the object holder 36 by bolts 43 and 44. The rear end of the screw 37 is provided with a gear 45 for engaging a worm 46 which is fixed to a shaft 47 journalled in bearings 48 and 49 on the carriage 30. A ratchet 50 is fixed near the outer end of the shaft 47 for receiving power intermittently to drive the screw 37.

Freely rotatable on the shaft 47 is an arm 51 carrying a pawl 52 for engaging the ratchet 50. The pawl 52 is pivoted at 53 on the arm 51 and a spring 54 urges the pawl into engagement with the teeth of the ratchet 50. A second arm 55 immediately adjacent the arm 51 is also freely rotatable on the shaft 47. A pin 56 is secured to the arm 55 and extends between an edge of the arm 51 and a stop 57 on the pawl 52 thus forming a lost motion driving connection between the arms 51 and 55. The pawl 52 has a cam portion 58 in the path of the pin 56 so that when the pin 56 is moved toward the stop 57, the pawl 52 is pivoted out of engagement with the ratchet teeth before any rotary movement of the arm 55 is transmitted to the arm 51. One end of a link 59 is pivoted at 60 to the wall 14 while the other end is pivoted at 61 eccentrically of the arm 55. Thus when the carriage 30 is reciprocated by

eccentric 27, the link 59 will cause the arm 51 and pawl 52 to oscillate and turn the ratchet 50.

Adjacent the ratchet 50 on the side opposite the arms 51 and 55, a sector shaped pawl lifter 62 is freely rotatable on the shaft 47. The peripheral edge of the pawl lifter 62 cooperates with a rotatable extension 63 on the pawl 52 to hold the pawl out of engagement with the ratchet 50 and by changing the angular position of the pawl lifter 62, the amount of feeding movement imparted by the pawl is changed without the necessity of changing the length of the stroke. Fixed to the pawl lifter 62 is a gear 64 which engages a gear 65 on a shaft 66 journalled in a bearing 67 on the carriage 30. The shaft 66 is universally connected at 68 to an extensible link 69 which in turn is universally connected at 70 to a shaft 71 leading to the feed setting dial 72.

A gear 73 is fixed on the shaft 47 and meshes with a pinion 74 on a shaft 75 journalled in a bearing 76 on the carriage 30. The shaft 75 is universally connected at 77 to an extensible link 78 which is universally connected at 79 to a shaft 80 rotatably mounted in the wall 15 and carrying a crank 81. By means of the crank 81 acting through the gear 73 and pinion 74 the screw 37 can be rotated to return the object holder 36 from its forward position.

The extent of forward movement of the object holder 36 is limited by a shielding cam 82 pivotally connected at 83 to the carriage 30. As shown in Fig. 6 the left hand side of the shielding cam 82 is movable to a position where it engages the rotatable extension 63 on the pawl 52 to hold the pawl 52 out of engagement with the teeth of the ratchet 50 throughout its entire stroke. The right hand side of the shielding cam 82 is formed with a projection 84. As shown in Fig. 5 the projection 84 rests against a stop 85 on the carriage 30 when the shielding cam 82 is in its inoperative position. A trigger 86 is pivotally mounted at 87 on a bracket 88 fixed to the object holder 36, and is normally held in a vertical position by a spring 89. As the object holder 36 is fed forward the trigger 86 engages the stop 85 and the spring 89 is placed under tension. When the trigger 86 passes over the stop 85, the spring 89 snaps the trigger 86 into engagement with the projection 84 and the shielding cam 82 is moved to its shielding position so that even though the motor 25 continues to run and reciprocate the carriage 30, there will be no feeding of the object holder 36.

The front end of the object holder 36 is an internally threaded hollow socket 90 in which is seated a hollow spherical cup 91. A spherically surfaced nut 92 engages the inner surface of the cup 91 and is secured by a lock nut 93 to a shaft 94 extending through an aperture 95 in the cup 91. The shaft 94 terminates in a head 96 having a radial slot 97 and a pin 98 fixed in the object holder 36 holds the head 96 and shaft 94 against rotation. A nut 99 threaded in the hollow socket 90 is rotatably carried on the shaft 94 in engagement with the head 96. The nut 99 is rotatable by a handle 100 which extends through a slot 101 in the hollow socket on the object holder 36. A cover ring 102 serves to protect the interior of the socket against the entry of dust or dirt through the slot 101. The object or specimen to be cut is clamped in the cup 91 by a jaw 103 operated by a thumb screw 104.

The knife holder 12, which is substantially the same as that described in U. S. Patent 1,765,283 issued June 17, 1930, to W. L. Patterson and G.

B. Gallasch, has two spaced upright members 105 and 106 rigidly connected by a web 107. The upright members 105 and 106 are arcuate on their bottom surfaces and rest on the arcuate block 108 which is slidably mounted on the base 10 of the microtome. The center of this arcuate curve is the cutting edge of the knife. The block 108 can be locked in position on the base 10 by a handle 109 and carries a clamping member 110 under the control of a handle 111 for locking the knife holder 12 in desired position. Each of the upright members 105 and 106 has an aperture or bore 112 and an adjusting screw 113 extends from the knife clamp into this aperture or bore and terminates in an enlarged head 114. The enlarged head 114 for adjusting the knife vertically is thus rendered easily accessible. The up-rights 105 and 106 are provided respectively with rigid shields 115 and 116.

In operation, the dial 72 controlling the pawl lifter 62 is set for the desired thickness and the motor 25 is started at the desired speed by means of the switch 117 and governor 118. The motor drive is transmitted through the one-way drive 26, the shaft 24 and gears 23 and 22 to the eccentric 27 which reciprocates the carriage 30. This reciprocating movement causes the pawl 52 to rotate the ratchet 50 intermittently and, though shaft 47, worm 46, wheel 45 and screw 37, to feed the object holder 36 toward the knife holder 12. When the object holder 36 reaches the forward limit of its travel, the trigger 86 passes over the stop 85 and engages the projection 84 on the shielding cam 82 moving the cam 82 to a position where it holds the pawl 52 out of engagement with the ratchet 50. The carriage may be retracted by the crank 81 which serves to rotate the screw 37 through the wheel 45, worm 46, shaft 47 and gears 73 and 74.

From the foregoing it is apparent that we are able to attain the objects of our invention and provide a new and improved microtome which is durable and rugged in operation yet efficient and accurate in operation.

We claim:

1. In a microtome a base, a carriage reciprocably carried by said base, means for reciprocating said carriage, an object support slidably mounted on said carriage, a screw mounted on said carriage for moving said object support, a ratchet wheel mounted upon said carriage for rotating said screw, a pawl, an actuating link for said pawl pivotally carried by said base for actuating said ratchet wheel and means for disengaging said pawl from said ratchet upon predetermined movement of said object support in one direction.

2. In a microtome a carriage, an object support slidably mounted on said carriage, pawl and ratchet means for sliding said object support, shielding means movable to a position where said pawl is held out of engagement with said ratchet wheel, means mounted upon said object support to move said shielding means into its shielding position upon a predetermined travel of said object support and means on the support for holding the shielding means in shielding position.

3. In a microtome a base, a carriage reciprocably carried by said base, an object holder movably mounted upon said carriage, means including a pawl and a ratchet wheel for moving said object holder, shielding means carried by said carriage for shielding said ratchet wheel from said pawl, a trigger carried by said object holder

for moving said shielding means into shielding position, and a release for said trigger mounted on said carriage whereby said shielding means is moved quickly to its shielding position upon predetermined relative movement between said carriage and said object holder.

4. In a microtome a base, a carriage reciprocably mounted upon said base, an object support slidably mounted upon said carriage, a screw carried by said carriage for moving said object support, a ratchet wheel carried by said carriage for rotating said screw, a pawl arm oscillatably mounted on said carriage concentrically with said ratchet wheel for actuating said ratchet wheel, a pawl carried by said pawl arm, a pawl lifter rotatably mounted on said carriage concentrically with said ratchet wheel and means for moving said pawl lifter whereby the extent of rotation of said ratchet wheel may be changed without changing the extent of the oscillation of said pawl arm.

5. In a microtome having a base, a wall carried by said base, a carriage reciprocably carried by said base, an object holder movably carried by said carriage, a screw rotatably mounted on said carriage for moving said object holder, a ratchet wheel carried by said carriage for actuating said screw, means independent of said ratchet wheel for actuating said screw, a handle rotatably carried by said wall and means interconnecting said handle and said actuating means.

6. In a microtome a casing, a carriage reciprocably carried by said casing, mechanism for reciprocating said carriage, an object holder slidably mounted on said carriage, means on said carriage for sliding said object holder longitudinally, a ratchet wheel rotatably mounted on said carriage for actuating said means, a pawl pivotally carried by said carriage for actuating said ratchet wheel, and a link pivotally connected to said casing and operatively connected to said pawl so that reciprocation of said carriage actuates said pawl.

7. In a microtome a casing, a knife holder mounted on said casing, guides mounted on said casing, a carriage reciprocably mounted on said guides, an object support slidably mounted on said carriage, a screw carried by said carriage for sliding said object support toward said knife holder, a ratchet wheel carried by said carriage for rotating said screw, an arm pivotally mounted on said carriage coaxially with said ratchet wheel, a pawl mounted on said arm for engaging said ratchet wheel, a link operatively connected eccentrically of said arm and pivotally connected to said casing, and means for reciprocating said carriage.

8. A microtome comprising an object holder adapted to be reciprocated, a knife holder having a cylindrically curved base upon which it is movably mounted, said curved base defining the arc of a cylinder whose axis lies above said knife holder, said knife holder having a large bore therethrough extending substantially parallel to said cylinder axis, clamping means on said knife holder for securing a knife blade therein, spaced means for leveling said knife blade and for moving same into coincidence with said cylinder axis, said means extending into said bore.

9. In a microtome a base, an adjustable knife

holder mounted on said base, a knife adjustably carried by said knife holder, guides mounted on said base, a carriage reciprocably mounted on said guides, an object support slidably mounted on said carriage, a screw carried by said carriage for sliding said object support toward said knife holder, means for adjusting said knife holder for varying the cutting angle of said knife relative to said object support, means for locking said knife holder in adjusted position, a ratchet wheel carried by said carriage for rotating said screw, an arm pivotally mounted on said carriage coaxially with said ratchet wheel, a pawl mounted on said arm for engaging said ratchet wheel, a link operatively connected eccentrically of said arm and pivotally connected to said base, and means for reciprocating said carriage.

10. A microtome comprising a base, a knife carried by said base, a carriage reciprocably carried by said base, an object support slidably mounted on said carriage for movement toward and from said knife, a screw operatively connected to said support for moving said support toward said knife and a feeding mechanism operatively connected to said screw for intermittently rotating said screw, said mechanism comprising a rotatably mounted ratchet wheel, an arm rotatably mounted substantially coaxially with said ratchet wheel, a pawl pivotally mounted upon said arm for feeding engagement with said ratchet wheel, actuating means for oscillating said arm and means interconnecting said actuating means and said arm for withdrawing said pawl from said ratchet wheel upon movement in its non-feeding direction.

11. A microtome comprising a base, a knife carried by said base, a carriage reciprocably carried by said base, an object support slidably mounted on said carriage for movement toward and from said knife, a screw operatively connected to said support for moving said support toward said knife and a feeding mechanism operatively connected to said screw for intermittently rotating said screw, said mechanism comprising a rotatably mounted ratchet wheel, an arm pivotally mounted coaxially with said wheel, a pawl pivotally mounted on said arm for feeding engagement with said ratchet wheel, a second arm pivotally mounted coaxially with said ratchet wheel and said first arm, a lost motion connection between said arms, cam means between said second arm and said pawl for withdrawing said pawl from said ratchet wheel during said lost motion upon movement in its non-feeding direction and means for oscillating said second arm.

12. In a microtome, a knife, an object support, means for reciprocating said support, feeding means for moving said support towards said knife in a direction perpendicular to the direction of reciprocation, a motor for driving both said means, means for disengaging said feeding means, and means on said support for actuating said disengaging means and holding said disengaging means in disengaging relation, upon a predetermined extent of movement of said support toward said knife.
